SUSPENSION RAILWAY TRAIN

Arthur J. Di Stasi, Trenton, N. J.

Application July 22, 1955, Serial No. 37,106

Term of patent 14 years

(Cl. D66—1)

*Fig. 3.**Fig. 4.*

Fig. 1 is a fragmentary front perspective view of a suspension railway train embodying my new design;
 Fig. 2 is a fragmentary rear perspective view;

Fig. 3 is a side elevation thereof in its entity, the sides not shown being substantially similar to the sides shown and the bottom is plain; and

Fig. 4 is an enlarged detail perspective view of the flexible car-coupling enclosure.

The characteristic features of my design reside in the portions shown by means of full lines in the drawing.

I claim:

The ornamental design for a suspension railway train, substantially as shown and described.
